UNITED STATES PATENT OFFICE.

JOHN J. BROPHY, OF PHILADELPHIA, PENNSYLVANIA.

MACHINE FOR TREATING TEXTILE MATERIALS OR PRODUCTS.

Application filed March 14, 1922. Serial No. 543,674.

To all whom it may concern:

Be it known that I, JOHN J. BROPHY, a citizen of the United States, residing at Philadelphia, county of Philadelphia, and 5 State of Pennsylvania, have invented certain new and useful Improvements in Machines for Treating Textile Materials or Products, of which the following is a specification, reference being had to the accompanying drawings.

My invention relates generally to machines for treating textile materials or products, and more especially to those wherein the articles to be treated are mounted or 15 hung on sticks or poles, such for example as so called rotary dyeing machines which are commonly used for dyeing, bleaching, scouring or washing skein yarns and the like. In these machines, the sticks or poles 20 are sustained between rotating wheel frames or spiders which carry their charges through a trough filled with the treating liquor. Provisions are usually made for permitting ready removal of the sticks or 25 poles for facilitating loading and unloading of the machines, and means are also provided for effecting intermittent independent rotation of the poles in the course of the movement of the supporting frames to insure 30 exposure of all portions of the skeins to the treating liquor. The retention of the poles in the devices heretofore designed for detachably securing them to the supporting wheel frames or spiders, was invariably effected by aid of springs. On account of 35 the corrosive nature of the treating liquids ordinarily used, the springs were either destroyed in a short time or lost their tension with the result that the poles dropped 40 from the wheel frames and caused entanglement or other damage to the materials under treatment. Springs were also used to prevent retrograde movement of the poles upon 45 being rotated in the manner aforesaid. These springs were likewise rendered useless through 50 the action of the treating liquors with the result that some portion of the skeins remained in contact with the poles throughout the treating period and became either streaked or unevenly dyed.

The main object of my invention is to overcome the various difficulties pointed out, and how this desiderata may be secured will be readily understood from the detailed description of a typical embodiment of my invention which follows.

In the drawings, Fig. I is a view in transverse section of a dyeing machine conveniently illustrating my invention, portions thereof being shown broken away and shown 60 in section so as to expose certain important details.

Fig. II is a detail view on an enlarged scale showing one of the engaging devices whereby the poles are removably secured to 65 the supporting frames or spiders.

Fig. III is a view similar to Fig. II, but showing the relation of the parts of the pole engaging device when inverted during half the rotation of the supporting wheel or 70 frame.

Fig. IV is a perspective view of the cover member of the engaging device.

Fig. V is a detail view showing the means whereby retrograde movement of the poles 75 is prevented.

Fig. VI is a section taken as indicated at VI—VI in Fig. V; and

Fig. VII is a view similar to Fig. II of the form of engaging device used in attaching 80 the inner set of poles.

The dyeing machine herein shown for the purpose of illustrating my invention comprises a trough 1 for a treating liquor which may be covered over by panels removable 85 to gain access to the interior, and means, in the form of a wheel 2, for carrying materials which are to be treated, through the trough. Said wheel consists of two spiders 3—4 secured in spaced relation, upon a shaft 90 5 which may be journalled for rotation in bearings mounted on the tops of the side walls of the trough. Horizontally sustained between the spiders 3—4 near the peripheries of the same with provisions for permitting removal, are a series of sticks or poles 7—7, and within a circle near the center of the wheel, a series of companion poles 8—8. The sticks or poles of these two series are used in pairs for hanging or mounting 100 skeins "S" of yarn or other materials in loop form.

The poles 7 of the outer circle are supported at one end by engaging devices 10 which are secured to the inner face of the 105 spider 3. Each of the devices 10 comprises a member 11 with a cup 12 for receiving the pole end, and a member 13 which serves as a closure for the cup and thus retains the pole end in the cup. In the course of being 110 guided toward the receiving cup which act may be facilitated by the provision of an

integral ledge 14 of the member 11, the pole end encounters one edge of the cover member 13 as a result of which the latter is swung against gravity (as suggested in dotted lines in Fig. II) about its suspension pivot 15 in a direction crosswise of the cup 12 to an extent limited by a stop 16. Immediately upon the seating of the pole end within the cup 12 the cover member automatically swings back to the normal or full line position in which it is maintained by virtue of its engagement with a stop shoulder 17 formed on the ledge 14 or if the latter is omitted it may be formed on the cup 12 while the engaging device passes through the first and second quadrants of the rotation of the wheel as considered with reference to Fig. I. In this way, a notch 18 in the cover member is held in registry with the cup while the engaging device passes into the second quadrant, so that the pole end can move or drop into the notch to a position across the line of juncture of the cup and cover members. The pole thus acts to lock said members together, and consequently, is prevented from falling out of the engaging device while passing through the third and fourth quadrants of rotation of the wheel 2. The last described action will be readily understood upon cursory examination of Fig. III.

At their opposite ends, the poles 7 are supported by engaging devices 20 which are secured to the spider 4 at the side of the machine nearest the observer. One of these devices is shown in detail in Figs. V and VI where it is shown as comprising a cylindrical portion 21 which is rotative in an aperture in the spider 3 and held from longitudinal displacement by a star wheel 22 at its outer end, and an attached ratchet disk 23 at its other end. Said disk has a group of outstanding lugs 24-24 between which the squared end 25 of the pole 7 is engaged. As the wheel 2 revolves, the star wheel encounters a detent 26 (Fig. I) projecting inwardly from the cover of the trough 1. As a consequence of this engagement, the pole is given a slight independent movement so that the position of the skeins with relation thereto is shifted at each rotation of the wheel. Retrograde movement of the pole is prevented by gravity pawls 27-28. (Fig. V) which alternatively cooperate with the ratchet disk 23 during each rotation of the wheel. Pins 29-29 serve as stops to prevent excessive free motion of the pawls.

The poles 8 in the inner circle of the wheel 2 are supported at one end by insertion in openings or by other suitable means and at their opposite ends by engaging devices 30 whose construction will be best understood from Fig. VII of the drawings. The device as there shown is generally similar to the device 10 in that it comprises a cup member

31 and a relatively movable cover member 32. In this instance however, the member 31, instead of but one cup, may have a series 33-33 with guide ledges 34-34 intervening. The cover member 32 slides under guidance of pins 35-35, and under limitation of slots 36-36 through which said pins pass. The guards 37 extending about the retaining notches 38 of the cover member are flanked at one side by lugs or projections 39 which, in the course of introduction of a pole end, are engaged by the latter to cause the cover member to be moved aside in a manner similar to that previously explained. As the wheel 2 is rotated in the direction indicated by the arrow in Fig. VII, gravity becomes effective in causing the cover member to be shifted to closed position before its entry into the second quadrant, and, in the continued movement of the wheel, the pole end slips into the retaining notch 38 to lock the members 31 and 32 together as already understood. The cups 33-33 can be selectively used to vary the spacing of the pole 8 with respect to the companion pole 7 in the outer circle for accommodation of skeins of different sizes, as suggested in dot and dash lines in Fig. I. The poles 8 are rounded at both ends so that they may rotate freely and follow the movements of the skeins induced by intermittent rotation of the poles 7 under action of the star wheels 22. It will be apparent that the pole retaining devices of the inner and outer series may be transposed if desired, that is, the device shown in Fig. II may be used at the inner portion of the wheel and the device shown in Fig. VII at the periphery. Also, the device of Fig. II may be used entirely at both the inner and outer peripheries of the wheel, and the device of Fig. VII may be used alone in the same manner.

Having thus described my invention, I claim:

1. A machine for treating textile materials including a pair of spaced rotatable frames capable of sustaining horizontally between them, sticks or poles for hanging the articles being dyed; and engaging devices carried by said frames each comprising a cup for receiving a pole end, and a cover movable crosswise of said cup to permit insertion of the pole end, and having a complementary notch into which, when the device as a whole is partially or completely inverted during rotation of the frames, the pole end drops to a position across the line of juncture of the cup and cover to hold the latter locked against movement so long as the engaging device remains partially or completely inverted.

2. A machine for treating textile materials including a pair of spaced rotatable frames capable of sustaining horizontally between them, sticks or poles for hanging the articles

being dyed; and engaging devices carried by said frames each comprising a cup for receiving a pole end, and a cover capable of being swung about a pivot, against gravity, crosswise of the mouth of the cup to permit insertion of the pole end, and having a complementary notch into which, when the device as a whole is partially or completely inverted during rotation of the frames, the 10 pole end drops to a position across the line of juncture of the cup and cover to hold the latter locked against movement so long as the engaging device remains partially or completely inverted.

15 3. A machine for treating textile materials including a pair of spaced rotatable frames capable of sustaining horizontally between them, sticks or poles for hanging the articles being dyed; and engaging devices carried by said frames each comprising a cup for receiving a pole end, and a cover capable of being swung about a pivot, against gravity, crosswise of the cup in a direction away from a stop on the latter to 20 permit insertion of a pole end, and having a complementary notch which, when the device as a whole is being inverted during rotation of the frames, is maintaining in registry with the cup through the action of 25 the stop aforesaid, and into which the pole end drops to a position across the line of juncture of the cup and cover to hold the latter locked against movement so long as the engaging device remains partially or 30 completely inverted.

4. A machine for treating textile materials including a pair of spaced frames capable of sustaining horizontally between them, sticks or poles for hanging the articles 40 being treated, and carrying engaging devices each comprising a cup for receiving a pole end and having a fixed ledge forming a part of the cup for assisting in the guidance of the pole end to the receiving cup.

45 5. A machine for treating yarn in skeins, including two spaced frames capable of sustaining horizontally between them sticks or poles cooperative in pairs for mounting the skeins, and engaging devices arranged in 50 substantially radially spaced pairs carried by said frames, each device having retaining cups or notches into which the pole ends can be selectively introduced so that the distance between the poles of each pair can be 55 varied in accordance with size of the skeins, by inserting the pole ends into one or the other of the cups.

6. A machine for treating textile materials including a revoluble frame carrying a 60 multiplicity of independently rotatable sticks or poles for mounting the articles be-

ing dyed; means whereby said poles are intermittently rotated during the movement of the frame aforesaid; ratchet wheels associated with said poles; and a pair of independently movable gravity actuated pawls cooperative with each ratchet located at opposite sides thereof and capable of becoming alternately active during each revolution of the frame in preventing retrograde 70 movement of the poles or simultaneously inactive.

7. In a machine for treating textiles including a frame and removable sticks, supporting devices for the sticks including co- 75 operating recessed members separable to receive the stick end and closing upon the stick, the latter constituting a lock preventing separation of the members when held partially within each member, but permitting separation of the members when enclosed wholly by one member.

8. In a machine for treating textiles including a frame and removable sticks, supporting devices for the sticks including a 85 recessed member to receive the stick end, a recessed latch member covering the recessed member and a ledge leading to the recess, whereby a stick end may be rested on the ledge and guided for movement toward 90 the recesses automatically pushing aside, the latch member so as to enter the recess.

9. In a machine for treating textiles including a frame and removable sticks, supporting devices for the sticks, including a 95 member having a series of recesses, a movable latch member covering the recesses, and a ledge adjacent each recess upon any one of which the stick end may be rested and moved toward the adjacent recess, and a series of 100 abutments carried by the latch member, one adjacent each ledge for engagement by the stick whereby the latch member may be automatically pushed aside by movement of 105 the stick end when entering a recess.

10. In a machine for treating textiles including a frame and two concentric annular series of sticks, means for supporting the sticks of one series including a plurality of supporting members each having a series 110 of radially arranged recesses whereby the sticks may be selectively entered into any one of said recesses to vary the spacing of the sticks relative to those of the other series.

In testimony whereof, I have hereunto 115 signed my name at Philadelphia, Pennsylvania, this 10th day of March, 1922.

JOHN J. BROPHY.
